LOOSE-LEAF BINDER

John A. Rennie, Laurelton, N. Y., assignor to
Boorum and Pease Company, Brooklyn, N. Y.,
a corporation of New York

Application May 16, 1946, Serial No. 670,174

3 Claims. (Cl. 129—24)

1

The invention relates to a loose leaf binder and particularly to the binding mechanism in a ring book.

The object of the invention is to produce a binder which is attractive in appearance and which at the same time can be sold at a minimum price. More specifically the object is to do away with means on the outside of the back of the cover for holding the binding mechanism in the cover, and at the same time both provide a sturdy, durable binder and eliminate as many steps as possible in the manufacture of the device, and reduce the number of parts of the device, thus reducing the manufacturing expense, so that the binder can be sold at a minimum price, without reducing its efficiency.

These objects are attained by the mechanism described in the following specification including the accompanying drawings which form a part of the specification, and in which:

Figure 1 is a side elevation, partly broken away, of a shield forming part of the present invention;

Figure 2 is the similar view of the base showing parts broken away and showing part of the shield in dotted lines;

Figure 3 is a top plan view of the shield shown in Figure 1;

Figure 4 is a top plan view of the base shown in Figure 2, additional parts of a loose leaf book being shown partly broken away;

Figure 5 is a cross-section on a line analogous to 5—5 of Figure 6, through a complete loose leaf book embodying the invention, part of the cover and lining being shown broken away;

Figure 6 is a longitudinal section through an assembled base and shield, other parts being omitted for clarity;

Figure 7 is a cross-section on an enlarged scale, of a detail taken on the line 7—7 of Figure 2;

Figure 8 is a similar cross-section of a modified form of prong.

In the drawings are shown the parts of a binding mechanism including a novel base plate 10, ring bearing means 11 to which are attached ring valves 12, and a cooperating shield 13.

The novel base plate 10 comprises a longitudinal plate or strip 14 from the material of which a pair of prongs 15, 15' is struck up near each end of the plate, leaving corresponding cavities 16 in the plate adjacent each prong. Each prong is preferably formed with a shoulder 17 just below a terminal finger 18 of less width than the shoulders of the prong. To give the prongs greater strength, they are preferably bent so as to have an arcuate cross-section as shown particularly in

2

Figure 7. However, other configurations may be used for the prongs. A modification with a different cross-section is shown at 15a in Figure 8.

The shield 13, which cooperates directly with the base plate 10 in a novel manner, is illustrated in the drawings as constructed with a depressed area or cup 19 near each end and at the center of the width or narrow dimension of the shield, within which depression are slots 20 of a size suitable to receive the reduced ends 18 of the prongs. In the embodiment illustrated in the drawings, the shield 13 comprises a curved strip preferably with a flange 21 along each edge to receive the edges of the ring bearing means 11, and notched in usual manner at 22 to permit the passage of the rings 12.

At Figure 5, there is illustrated a loose leaf book embodying the invention. The book is illustrated as having a cover 23 and lining 24 carrying the binding mechanism. As shown particularly in Figures 4 and 5, the base plate 10 is secured in the book between the cover and the lining which are customarily glued or cemented to each other and to the plate 10.

In the completed binder as shown particularly in Figure 5, the assembled binding mechanism comprises plate 10 and ring bearing means 11 placed above the base plate, and shield 13 placed above the plate and the ring bearing means. The ring bearing means, not shown in detail, is so proportioned or cut away as to permit the passage of the prongs 15, 15' from the base plate 10 through or past the ring bearing means into slots 20 in the shield 13 above said means. The fingers 18 of the prongs extend through the slots 20, and are folded over as shown particularly in Figure 6, thus holding the plate 10, ring bearing means 11 and shield 13 assembled with each other and with the cover 23. The ends of the prongs lie wholly within the depression 19 and thus lie below the surface of the shield 13 so that there is no danger of their contacting and tearing the paper sheets in the ring book. The bottom of the depression 19 in the shield rests upon the shoulder 17 of the prongs thus spacing the shield any desired distance above the base and the ring bearing means.

The prongs 15, 15' which are continuous with the material of the strip 14, are of the same thickness as the rest of the base plate 10. The curved configuration of the prongs gives them great strength and thus permits the use of thin strip material for making the base plate 10. The use of a thin rather than a thick base plate is an advantage both because it helps to keep the

binder light and thus easy to handle and also because keeping at a minimum the amount of material used, helps to keep the selling price at a minimum.

By striking up the prongs 15, 15' from the strip 14, the amount of material used is kept at a minimum and the completed binder is both lighter to handle and less expensively manufactured.

In manufacturing a binder embodying the invention, each of the parts 10 and 13, namely the base plate and the shield, can be struck out from a sheet of material and completely formed in a single operation. Thus, in making the base plate 10, a stroke can cut out the configuration of the strip 14 and the outline of the prongs 15, 15' and their cavities 16. As the cutting instrument is withdrawn, the prongs can be folded up substantially at right angles with the strip 14. At the same time a curved configuration can be given to the prongs as shown particularly in Figure 7, and a curved configuration can be given to the strip 14 as shown particularly in Figure 5.

Similarly a single stroke is used to cut out the blank of the shield 13, make the depression 19 and punch the slots 20 therein. In the same before being punched operation the shield is curved and flanges 21 are formed by passing through a forming roller. Binders heretofore known have required a larger number of parts and more operations to put them together.

In assembling the binder, the base plate 10 is placed along the back 25 of the cover 23 and the lining 24 is then secured in place, covering the edges of the base plate but leaving the prongs exposed. In the meantime the remaining parts are assembled together, that is to say, a pair of ring bearing means 11 with its rings 12 is assembled within the flanges 21 of the shield 13. The only remaining operation is to insert the fingers 18 of the prongs 15 through the slots 20 and to turn down the fingers into the depressions 19 in the shield.

The provision of a pair of prongs 15 at one end of the plate 10 curved oppositely, and another pair of prongs 15' at the other end, also curved oppositely, provides stability and stiffness to the structure so as to strongly resist any tendency to collapse in case pressure is applied in opposite directions to the base plate and shield.

This is a great saving in operations over what has been necessary in assembling binders of known construction. It has a further advantage of being a simple procedure which can be practised even by operators who have not had special training.

It is to be understood that changes and variations may be made without departing from the spirit and scope of the invention as defined in the appended claims.

5 I claim:

1. In a loose leaf binder having spaced rings, ring carrying means, a cooperating shield on one side of said ring means with slots in the mid-portion of its width, a base plate on the other side of said means having near its ends and integral therewith longitudinally spaced hollow prongs arcuate in cross section and struck upward from the surface of the base plate, the concave surfaces of said arcuate prongs facing oppositely to afford added resistance against opposite lengthwise pressures exerted on said base plate and shield, each prong having at its free end a terminal finger of reduced width, said fingers passing through the slots in the shield and being bent over to secure the base, ring carrying means and shield together, said shield and said base plate cooperating to hold said ring carrying means therebetween.

2. In a loose leaf binder having spaced rings and means carrying said rings, a cooperating slotted shield on one side thereof, a base plate on the other side of said ring-carrying means having a pair of longitudinally spaced prongs arcuate in cross section near each end thereof struck up therefrom, the prongs of each pair having their concave surfaces facing oppositely affording stability and stiffness resistant to opposite lengthwise pressures exerted on said base plate and shield, each prong having on its free end a shoulder for supporting the shield and a terminal finger of reduced width passing through a slot in the shield and bent down to secure the shield and plate together and holding said ring bearing means therebetween.

Certificate of Correction

Patent No. 2,571,945

October 16, 1951

JOHN A. RENNIE

It is hereby certified that error appears in the printed specification of the above numbered patent requiring correction as follows:

Column 1, line 45, for "valves" read *halves*; column 4, line 8, before "means" insert *carrying*;

and that the said Letters Patent should be read as corrected above, so that the same may conform to the record of the case in the Patent Office.

Signed and sealed this 26th day of February, A. D. 1952.

[SEAL]

THOMAS F. MURPHY,
Assistant Commissioner of Patents.
